CLOSURE FASTENING FOR TROUSERS

Philip Friedman, New York, N. Y.

Application September 22, 1950, Serial No. 186,140

2 Claims. (Cl. 2—234)

1

This invention is an improvement in trousers; especially trousers that are divided in the middle from the waist down in front, and have means for securing the edges of the divided portions together.

An important object of this invention is to provide a pair of trousers with a fastening device that is attached to the divided front of the trousers or "fly" in a secure manner, to avoid tearing the cloth or otherwise letting the fastener be loosened.

The nature of the invention is fully described herein and a preferred embodiment of the improvement is illustrated in the accompanying drawings, whereon:

Figure 1 is an inside view of part of a pair of trousers with a fastener attached, in unfinished condition.

Figure 2 is a similar view of the same part with the fastener, all finished; and

Figures 3 and 4 show details.

In Figure 3 the numerals 1 and 2 indicate the end portions of the waistband 9 of a pair of trousers, divided in front to make the fly, with a row of stationary fastening elements 3 along each edge of the fly, to be operated into engaging relation and released from one another by the usual slideable fastener, not shown. The elements 3 are carried by a strip 8 secured to the trousers along each edge of the fly. One end portion 2 of the waistband carries a flat hook member 4 which can be detachably engaged with an elongated metal strip or loop 5 made fast at its extremities to the opposite end portion 1 of the band. The cloth of the trousers is shown in part at 6 and at the fly the cloth is turned over to make an inside flap 7. Only one side of the fly is illustrated in Figures 1 and 2, but each side will have a flap 7. The waistband is sewed to the cloth 6 and the flaps 7, and a portion 12 at each end of the band is folded over and secured to the top edge of the adjacent flap 7.

A small piece of cloth 13, nearly square, is attached to the horizontal junction of the flap 7 and portion 12. This piece or flap 13 carries the member 4 on its inner face. The hook member 4 has a pointed projection 15 which pierces the flap 13 and is pressed flat against the face that is the outer face thereof when the garment is finished. Between the hook 4 and the flap 13 is a piece of stiff reinforcing material 14, and the projection 15 goes through this lining piece 14 also. The flap 13 is then turned up against the portion 12 and sewed in place. The hook member 4 is strongly held by the flap 13 and the lining 14 and cannot be torn loose.

The hook member 4 can have openings 17 for stitches and the projection 15 can be omitted. In either case the front edge 16 of the flap 13 is turned in and stitched to the portion 12 above and below the hook member. See Figure 1. The front lining 14 along its front edge lies under the edge portion 16 and the rear edge of both the flap 13 and the rear edge of the lining 14 are stitched fast to the portion 12 and the band as indicated at 20.

2

The upper and lower edges 10 and 18 respectively of the whole waistband and the portion 12 are turned in and sewed together, and the upper edge of the piece 13 is under the lower edge 18 of the turned over portion 12, before the piece is turned up. (See Figure 1.) After being turned the piece 13 lies with its top edge along the top edge of the portion 12. The stitches along these edges are indicated at 19.

- 10 The turned in edge 16 is attached to the portion 12 at both sides of the hook by stitches 21 and stitches not shown through the holes 17 at each side of the hook. The waistband has its lower edge 18 stitched to the inturned upper edge 11 of the cloth 6. The hook member 4 and the pieces 13 and 14 are set back a little from the adjacent extreme terminal edge of the waistband, so as to be overlapped along said edge by the portion 12.
- 15 20 Having described my invention, what I believe to be new is:

1. A garment having a divided waistband with separated ends at the front and a portion of said waistband at one end turned over and secured against the inner face of the waistband, a short piece having its lower end inserted and secured between the lower edge of said turned over portion and the adjacent portion of said band and turned up against said turned over portion, and a member having a hook and openings for stitches at both sides of the hook adjacent its front end secured to said piece between said piece and said turned over portion, with said hook exposed outside of said piece and overlapping same, said piece being secured to said band; and a lining secured between the member and said piece, and in contact with the entire length of said member and extending beyond the inner end thereof.

2. A garment having a divided waistband with separated ends at the front and a portion of said waistband at one end turned over and secured against the inner face of the waistband, a short piece having its lower end inserted and secured between the lower edge of said turned over portion and the adjacent portion of said band and turned up against said turned over portion, and a member having a hook and openings for stitches secured to said piece between said piece and said turned over portion, with said hook exposed outside of said piece and overlapping same, said piece being secured to said band; and a lining secured between the member and said piece, and in contact with the entire length of said member and extending beyond the inner end thereof, said short piece, said lining and said member being set back from the adjacent extreme terminal edge of said band.

PHILIP FRIEDMAN.
